Specification for Design.

Patented Apr. 27, 1920.

Application filed September 23, 1919. Serial No. 325,782. Term of patent 7 years.

To all whom it may concern:

Be it known that I, GILDEROY O. BURLEW, a citizen of the United States, residing in the city of Newark, in the county of Essex and State of New Jersey, have invented a new, original, and ornamental Design for a Tooth Cleaning and Polishing Device, of which the following is a specification, reference being had to the accompanying drawings, forming a part thereof.

In the drawings,
Figure 1 represents a front elevation of a

tooth cleaning and polishing device, illustrating my new design; and

Fig. 2 represents a side elevation of the same.

I claim:

The ornamental design for a tooth cleaning and polishing device, as shown.

GILDEROY O. BURLEW.
